DAMPER OPERATING MEANS

Phillip J. O'Brien, Sacramento, Calif.

Application April 4, 1933, Serial No. 664,358

2 Claims. (Cl. 126—288)

My invention relates to damper operating means and more particularly to means for raising and lowering to different positions a damper plate in a fire place or other passage whereby to regulate or cut off draft therethrough.

Among the salient objects of my invention are: to provide a revolute member having a plurality of straight surfaces positioned at different distances from its axis of rotation and at an angle 10 to the radial from said axis, said straight surfaces being adapted to be turned to underlie the damper plate whereby to hold it in different raised positions, depending on which of said straight surfaces is in operating position; to provide a revolute supporting rod or shaft for said revolute operating member on which said member can be moved to different positions toward and from the hinge or pivot connection of the damper plate, whereby to regulate the distance the damper plate 20 can be raised by said operating member; to provide an operating member of the character referred to which can be turned in either direction with the operative result, and, in general, to provide a practical, simple and economical damper 25 operating mechanism of the character referred to.

In order to explain my invention, I have shown one practical embodiment thereof on the accompanying sheet of drawings, which I will now describe.

30 Figure 1 is a vertical sectional view through a portion of a fireplace, showing my invention in place therein;

Figure 2 is a sectional view thereof taken on the line 2—2 of Fig. 1; and

35 Figure 3 is a sectional view taken on the line 3—3 of Fig. 1.

Referring now in detail to the drawing, 4 and 5 40 designate a fire-place structure, which can be of any desired construction, with 6 indicating the open side thereof and 7 indicating the passageway upwardly therethrough to the flue. Across the top of the arch or open side 6, is shown an angle iron 8, which supports the structure above the opening 6. Hingedly connected to the inner 45 upper edge of said angle iron 8, as at 9, is a damper plate 10, adapted to close down over the passageway and to close the same, as shown in full lines, said damper plate being shown in section. It will be understood, of course, that it 50 covers the entire passageway up through the structure.

I will now describe the operating means for moving and holding the damper plate in different raised positions of adjustment. Inserted through 55 the front structure 5 and the inner plate of the

angle member 8, is a tube 11, having threaded on its outer end, in the structure 5, a dial head 12, having around its face, as seen in Fig. 3, the numerals 1, 2, 3, 4, 5 and 6, representing six different positions. On the inner end of said tube 11 is a nut 13, screwed up against the angle member as shown, whereby to firmly anchor said tube in place through the wall structure 5. An operating rod 14 is inserted through the tube 11, and provided on its outer end with a knob, or handle means 15, which can be of a design to match other hardware in the home. There is also secured on said operating rod a collar or portion 16 having a point or finger 16' designed to move over the dial numerals on the dial head 12, as shown in Figs. 1 and 3. 15 On the inner end of said operating rod 14 is a collar 17, with set screw 17' to secure it in place, to prevent longitudinal movement of said rod through the tube 11. A spring washer 18 is placed between the end of the tube 11 and said collar 17, 20 to give a certain yielding frictional action to said operating rod.

Adjustably mounted on said operating rod 14, 25 is a damper operating member 19, secured in place by means of a set screw 20, through a hub or boss 19' formed on said member 19, as clearly indicated. I have illustrated this member of hexagonal form, with a portion cut out, as at 21, to lighten it in its heavier side. This operating member is eccentrically positioned on the operating rod, as will be seen from Fig. 2, whereby the straight edges thereof are positioned at different distances from the axis thereof, thus making it possible, as said operating member is turned and engages the underside of the damper plate 10, to raise said damper plate to different angular positions, one position being shown in light broken lines in Fig. 1. The corners or junctures between the different straight edges are slightly rounded, as shown to facilitate the turning of said operating member.

By providing damper-plate-engaging edges, it will be understood that any tendency of the operating member to turn under the weight of the damper plate is eliminated and the operating member will stay in any one of the six different positions it is turned to.

If these damper plate engaging edges were hollowed out, as indicated at H, in light broken lines on the member 19, Fig. 2, it will be seen that there would be two spaced engaging points, a and b, to underlie the damper plate and the result would be the same and it could not turn. So whatever the shape of the damper operating member, if there are two engaging and support- 55

ing points, spaced apart, underlying the damper plate, it will not turn under the weight of said damper plate, and if these are at different distances radially from the axis, the damper plate will be raised and held at different raised or open positions. In Fig. 1, the damper is shown closed in full lines, and in raised position in light broken lines. If the operating member is moved on the operating rod 14 closer to the collar 17, it will be evident that the same rotative movement thereof will raise the damper higher, and if the operating member 19 is moved outwardly toward the end of the rod 14, its rotative movement will not raise the damper so high.

15 It will also be seen that the operating member 19 can be turned in either direction by means of the hand knob 15, and the operation is the same, as the member will make a complete revolution in either direction.

20 While I have shown one form of operating member, I am aware that changes can be made without departing from the spirit of the invention, and I do not, therefore, limit the invention to the showing made, except as I may be limited by the hereto appended claims.

I claim:

1. In combination with a damper plate hingedly mounted at one side to be raised and lowered at its other side, an operating shaft un-

der said plate and extending at right angles to the hinge axis of said plate, an operating member on said shaft and eccentrically mounted, said operating member having peripheral plate engaging portions at different distances radially from said shaft to engage and lift said plate different distances as said shaft and operating member are turned, each of said plate engaging portions engaging and supporting said plate on its underside above said shaft and at both sides 10 of a vertical through said shaft, whereby to prevent turning of said operating member by the weight of said plate.

2. In combination with a damper plate hingedly mounted at one side to be raised and lowered at its other side, an operating shaft under said plate and extending at right angles to the hinge axis of said plate, an operating member eccentrically mounted on said shaft and adjustable longitudinally thereof, said operating member having a plurality of peripheral plate engaging portions at different radial distances from said shaft to engage and support said damper plate at different angles, each engaging portion engaging said plate on its underside at 25 opposite sides of a vertical through said shaft, whereby said plate weight does not turn said operating member and shaft.

PHILLIP J. O'BRIEN.
